CLAIM

The ornamental design for dishrack with drain board as shown and described.

DESCRIPTION

FIG. 1 is a front perspective view of the dishrack with drain board showing my new design;

FIG. 2 is a bottom perspective view thereof;

FIG. 3 is a top elevation view thereof;

FIG. 4 is a bottom elevation view thereof;

FIG. 5 is a front elevation view thereof;

FIG. 6 is a back elevation view thereof; and,

FIG. 7 is a left side elevation view thereof, the right-side elevation view is a mirror image of the left side elevation view.

The broken lines in the drawings depict portions of the dishrack with drain board that form no part of the claimed design.
